UNITED STATES PATENT OFFICE.

GUSTAVE MICHAELIS, OF LOS ANGELES, CALIFORNIA.

FLY-TRAP.

1,186,489.

Specification of Letters Patent.

Patented June 6, 1916.

Application filed February 8, 1915. Serial No. 6,746.

To all whom it may concern:

Be it known that I, GUSTAVE MICHAELIS, a citizen of the Empire of Germany, residing at Los Angeles, in the county of Los Angeles and State of California, have invented new and useful Improvements in Fly-Traps, of which the following is a specification.

This invention relates to fly traps and the 10 principal object is to provide a collapsible fly trap.

It is also an object to provide a fly trap which can be readily formed with a sheet metal frame.

15 It is also an object to provide a collapsible fly trap with panels having a sheet metal frame which may be readily replaced.

It is a still further object to provide a fly trap which may be either supported by 20 legs on the surface of a table or that may be suspended up out of the reach of children.

In the drawings accompanying this specification, Figure 1 is a perspective view of the trap showing a portion of one of the 25 screen panels broken away. Fig. 2 is an enlarged vertical cross section through one side of the structure. Fig. 3 is a transverse cross section in detail of one of the leg members, showing the panels locked there- 30 in. Fig. 4 is a detail in section showing the bait receptacle.

Heretofore in the manufacture of fly traps, their naturally bulky shape has been the cause of increased freight rates and has 35 required greater space in which to store those not exhibited in stores, and their appearance has been rather inartistic due to the harsh lines resulting from the use of thick wooden frames. This invention over- 40 comes the above difficulties and provides for the use of thin sheet metal which can be built lighter than the ordinary wooden structures and more economically, and the parts are susceptible of a bright finish.

45 More specifically in the drawings, 5 designates standards shown as a right-angle strip of metal, having grooves 6 pressed up outwardly on each of the component webs of said standards; these grooves 6 being provided with a slot or slots 7 intermediate the ends of the grooves, a portion of the metal within the confines of this slot forming a tongue 8, which is on the same plane as the web of the standard, which is adapted to 55 engage with a tongue formed on the side of the screen panel frame. Ears 9 are also

formed and project inwardly on the standards to form a stop or rest for the bottom member 10, the groove 6 not extending to the point where the stop ears 9 are formed. 60

Taking the parts in the process of assembling, the bottom 10 is also formed of sheet metal and is provided with an outwardly-extending flange 11, which bends back upon itself at the point where it is 65 adapted to rest upon the ears 9 to form an outwardly-extending web 12, which bears against the inner faces of the standards 5. To lock the flange 12 in relation to the lower bar 14 of the screen panel frame, a hump 15 70 is formed on this latter which engages below an elongated hump 16 formed upon the inner surface of the flange 12. The screen panels are provided with a screen 17, which is of such length as to extend from the ears 75 9 clear to the top of the standards and its edges are clamped within U-shaped bars. These are substantially rectangular in form. The side bars 19 are provided with a tongue 22 which slides within the groove 6 and engages with the tongue 8 on the standards. 80

In the drawings the structure is shown as cubical in form, but any number of sides, as desired, may be assembled, the angled corners or standards being shaped to accommodate a change of structure. 85

To lock the whole in place, a cover 23 is provided of substantially similar form to the bottom 10 and may be, for purposes of economy, formed in the same dies, having 90 a web 24 which extends upwardly and is formed over and downward to form a web 25, which slides over and embraces the ends of side bars 19 and the intervening screen 17.

To lock the same in position vertically-disposed hook ears 26 are formed on the upper ends of the corner members and are bent over inwardly to lock the whole in position. Upon a number of the corner posts a perforated ear 27 is formed, into 100 which a flexible member may be secured to suspend the structure in an elevated position, it being desirable at times to do this, as the insects which it is intended to catch at certain times are more numerous near 105 the ceiling.

To provide an entrance into the completed structure, an opening is provided in the center of the cover and adjacent the edges thereof the strikes 29 are upset from the 110 middle and adapted to receive the outer ends of a spring 30, which is locked in relation

to a circular door 31, by means of straps 32 formed on its periphery. The spring also acts as a handle to lift it.

The bottom 10 is also provided with an orifice preferably centrally located and of circular form, into which is projected a conical screen 33, provided with an enlarged outer opening at its flanged base, this flange being engaged by points 34 punched out of the metal, which are bent back and securely hold the conical entrance screen in position.

A bait receptacle is also provided, which consists of a circular pan 35, having a depression 36 annular in form therein, so that a platform is provided within the structure for the insects to stand upon and eat the preferably liquid bait filling the annular groove.

Spring arms 37 extend upwardly from the sides of the bait pan and having outwardly extending fingers 38, which project and engage within strikes 39 formed on the bottom to receive and lock the pan in position.

The advantages of this construction are that the insects are attracted entirely within the confines of the structure and feed immediately under the entrance, and in the normal tendency to rise find their way upwardly into the trap through the small upward opening in the conical entrance. By removal of the bait receptacle and the cover the device is readily inverted to remove the captured insects.

Having thus described my invention, what I claim is:

1. In an insect trap, the combination of a plurality of standards of angle form, side screen panels arranged to be disposed in the angles of said standards, each standard provided with stop ears adjacent the bottom thereof, a bottom panel disposed upon said stop ears and provided with an inlet for insects, a top panel provided with flanges having channels in which are disposed said side panels, and hook ears on said standards arranged to engage the flanges on said top panel.

2. In an insect trap, the combination of a plurality of standards of angle form, side screen panels arranged to be disposed in the angles of said standards, each standard provided with stop ears adjacent the bottom thereof, a bottom panel disposed upon said stop ears and provided with an inlet for insects, said bottom panel provided with flanges having channels in which are disposed said side panels, and a top panel detachably disposed on said side screen panels.

3. In an insect trap, the combination of a plurality of standards of angle form, side screen panels arranged to be disposed in the angles of said standards, each standard provided with stop ears adjacent the bottom thereof, a bottom panel disposed upon said stop ears and provided with an inlet for

insects, said bottom panel provided with flanges having channels in which are disposed said side panels, a top panel provided with flanges having channels in which are disposed said side panels, and hook ears on said standards arranged to engage the flanges of said top panel.

4. In an insect trap, the combination of a plurality of standard members of angle form, each leg of an angle provided with a groove, side screen panels having ears arranged to be detachably disposed in said grooves, a top panel detachably mounted on said side panels, and a bottom panel detachably mounted on said standards provided with an inlet for insects, said bottom panel having flanges at its edges provided with channels arranged to receive the side screen panels.

5. In an insect trap, the combination of a plurality of standard members of angle form, each leg of an angle provided with a groove, side screen panels having ears arranged to be detachably disposed in said grooves, stop ears provided on the legs of said standards adjacent the ends of the grooves, a bottom panel disposed upon said stop ears and provided with an inlet for insects, said bottom panel having flanges at its edges provided with channels arranged to receive the side screen panels, and a top panel detachably mounted on said side panels.

6. In an insect trap, the combination of a plurality of standard members of angle form, each leg of an angle provided with a groove, side screen panels having ears arranged to be detachably disposed in said grooves, a top panel having flanges at its edges provided with channels arranged to receive said side screen panels, and a bottom panel detachably mounted on said standards, said bottom panel provided with an inlet for insects.

7. In an insect trap, the combination of a plurality of standard members of angle form, each leg of an angle provided with a groove, side screen panels having ears arranged to be detachably disposed in said grooves, a bottom panel detachably mounted on said standards provided with flanges at its edges having channels arranged to receive the side screen panels, said bottom panel provided with an inlet for insects, and a top panel having flanges at its edges provided with channels arranged to receive the side screen panels.

8. In an insect trap, the combination of a plurality of standard members of angle form, each leg of an angle provided with a groove and stop ears adjacent the ends of said grooves, side screen panels having ears arranged to be detachably disposed in said grooves, a bottom panel arranged to rest on said stop ears having flanges at its edges.

provided with channels arranged to receive the side screen panels, a top panel having flanges at its edges provided with channels arranged to receive said side screen panels, 5 and hook ears on the upper part of said standards to lock the top panel in position.

In witness that I claim the foregoing I

have hereunto subscribed my name this 16th day of January, 1915.

GUSTAVE MICHAELIS.
